UNITED STATES PATENT OFFICE.

FRANK H. LANGSENKAMP, OF INDIANAPOLIS, INDIANA.

HEATING-COIL.

1,288,055.

Specification of Letters Patent. Patented Dec. 17, 1918.

Application filed October 15, 1917. Serial No. 196,569.

To all whom it may concern:

Be it known that I, FRANK H. LANGSEN-
KAMP, a citizen of the United States, residing
at Indianapolis, in the county of Marion
5 and State of Indiana, have invented a new
and useful Heating-Coil, of which the fol-
lowing is a specification.

In tomato-canning plants it is necessary
that the tomato pulp be cooked. This is
10 usually done in containers in which coils of
steam-carrying pipe are located, so that
these coils of pipe are immersed in the to-
mato pulp. Heretofore, these coils of pipe
have been provided with numerous fittings,
15 which are also immersed in the pulp. This
has made the assembling of the pipe coils
exceedingly difficult, and in addition the
pipe fittings have been a source of contami-
nation for the pulp, and have produced dis-
20 coloring of the pulp in their immediate
vicinity.

It is the object of my present invention to
provide a pipe coil unit, which may be as-
sembled separately and put in place in the
25 container as a unit; which has a single com-
pound supply and exhaust header which
also serves as a main support for the coil,
and which preferably passes through the
bottom of the container; and which has no
30 pipe fittings within the container so that
the contamination of the tomato pulp from
such fittings is eliminated.

The accompanying drawing illustrates my
invention. Figure 1 is a perspective view
35 of two nested pipe-coil units embodying my
invention, these units being shown sepa-
rately from the container; Fig. 2 is a verti-
cal section through a container in which said
two nested pipe coil units are mounted, the
40 header of the outer pipe coil unit being in
section; and Fig. 3 is a transverse section
through such header.

Each pipe coil unit consists of a header
10 and a plurality of pipes 11 bent into cir-
45 cular form with their ends brazed in sockets
12 on substantially opposite sides of the
header 10. When in use, the header 10 is
substantially vertical, and the pipe coils 11
substantially horizontal; but preferably the
50 receiving end of each pipe coil is slightly
higher than the discharge end thereof, as is
clear from Fig. 2, so that the water which is
condensed from the steam will flow with
the steam into the header. This is accom-
55 plished by properly offsetting the sockets 12.
The header 10 is hollow, and is provided

with a vertical partition 13, which extends
from the closed upper end of the header
downward nearly to the bottom thereof, the
lower end of such partition preferably being 60
curved and joined to one side of the header
so as to provide a receiving chamber 14 and
a discharge chamber 15. The receiving ends
of the pipes 11 communicate with the re-
ceiving chamber 14 through the correspond- 65
ing sockets 12, and the discharge ends of
such pipes communicate with the discharge
chamber 15. The header 10 is provided with
a laterally threaded opening 16 near its
lower end, communicating with the receiv- 70
ing chamber 14 near its bottom, so that
when the header is mounted in place a steam
supply pipe 17 may be threaded into such
opening 16. The lower end of the header 10
also has an axially threaded opening 18, 75
communicating with the discharge chamber
15, and receiving a pipe 19 for carrying off
the water which has condensed from the
steam.

The header 10 with its pipes 11 is as- 80
sembled as a unit on the bench, and after
being assembled is put in place as a unit in
a container 20, the lower end of the header
10 projecting downward through the bot-
tom 21 of the container. This container 85
bottom 21 is firmly clamped between a flange
22 on the header 10 and a clamping nut 23
mounted on a screw-threaded portion of
such header, suitable gaskets 24 being pro-
vided between such bottom and the flange 90
22 and nut 23. The part of the header below
the threaded portion receiving the nut 23 is
somewhat smaller than the remainder so as
to allow the free passage thereover of such
nut, and the openings 16 and 18 are pro- 95
vided in this smaller portion of the header.
The pipes 17 and 19 are screwed into the
openings 16 and 18 after the unit consisting
of the header 10 and pipes 11 has been
clamped in place by the nut 23. By thus 100
clamping the header 10 in place by the nut
23, the main support of the coil is provided,
but additional supports 25 may be provided
for the pipes 11 at convenient points. These
supports 25 rest either on the next lower 105
pipes 11 or on the bottom 21. Only one hole
through the bottom 21 of the container is
necessary to install each unit, this hole re-
ceiving the header 10, which serves both for
the inlet and outlet of the steam.

With this construction, there are no pipe
fittings within the container 20, the pipes

17 and 19 being attached to the header outside of such container. The brazed joints of the pipes 11 in the sockets 12 do not produce the contamination which is provided 5 by pipe fittings having leaded joints.

In operation, the steam from any suitable source enters the receiving chamber 14 by the pipe 17, and passes thence through the coils 11, where it gives up its heat and in 10 large part condenses. The water thus condensed passes to the discharge chamber 15, whence it is carried off by the pipe 19, preferably back to the source of steam supply. Any number of coil units may be nested to 15 gether, two such units being shown in the drawings.

I claim as my invention:

A pulp heater, comprising the combination of a container, and a pipe coil unit 20 mounted in said container, said pipe coil unit comprising a rigid header and a plu-

rality of pipes each bent into arc form and attached to said header at both ends of the arc, said arc-formed pipes being located at different longitudinal points along said 25 header and projecting generally transversely of the header, said header being provided with a longitudinal partition dividing it into two longitudinal chambers with which the pipe ends respectively communicate at 30 different longitudinal points of the header for the different pipes, said header projecting as a unit through the bottom of said container to provide both an inlet and an outlet for the steam and being clamped to said 35 bottom so that it also forms a rigid support for said pipe coil unit.

In witness whereof, I have hereunto set my hand at Indianapolis, Indiana, this ninth day of October, A. D. one thousand 40 nine hundred and seventeen.

FRANK H. LANGSENKAMP.
